United States Patent Office

Des. 182,832
Patented May 20, 1958

182,832

COMMODE

John J. Lubberts and Lambert J. Mulder, Grand Rapids, Mich., assignors to Tomlinson of High Point, High Point, N. C., a corporation of North Carolina

Application March 8, 1957, Serial No. 45,151

Term of patent 14 years

(Cl. D33—19)

FIG. 1

We claim:

The ornamental design for a commode, substantially as shown.
